UNITED STATES PATENT OFFICE.

CHARLES P. WOODBURY, OF KANSAS CITY, MISSOURI.

DESIGN FOR A CHARM, EMBLEM, BADGE, BUTTON, OR ARTICLE OF SIMILAR NATURE.

61,429.

Specification for Design. Patented Aug. 29, 1922.

Application filed May 15, 1922. Serial No. 2,257. Term of patent 14 years.

To all whom it may concern:

Be it known that I, CHARLES P. WOODBURY, a citizen of the United States, residing at Kansas City, Jackson County, Missouri, have invented a new, original, and ornamental Design for a Charm, Emblem, Badge, Button, or Article of Similar Nature, of which the following is a specification, reference being had to the accompanying drawing, forming a part thereof.

In the drawing—

Figure 1 is a face view of a watch charm embodying my design.

Figure 2 is a side edge view of the same.

I claim:

The ornamental design for a charm, emblem, badge, button, or article of similar nature, as shown.

CHARLES P. WOODBURY.
